UNITED STATES PATENT OFFICE.

DAVID J. JACOBS, OF CHICAGO, ILLINOIS.

DESIGN FOR A DISPLAY-STAND.

59,554.

Specification for Design.

Patented Nov. 1, 1921.

Application filed January 14, 1921. Serial No. 437,361. Term of patent 3½ years.

To all whom it may concern:

Be it known that I, DAVID J. JACOBS, a citizen of the United States, and resident of the city of Chicago, county of Cook, and State of Illinois, have invented a new, original, and ornamental Design for a Display-Stand, of which the following is a specification, reference being had to the accompanying drawings, forming a part thereof, and in which—

Fig. 2, is a side view of the same.

I claim:

The ornamental design for a display stand, as shown.

Signed at Chicago, in the county of Cook and State of Illinois, this 6th day of January 1921.

DAVID J. JACOBS.
